UNITED STATES PATENT OFFICE.

JOSEPH F. FITZPATRICK, OF WORCESTER, MASSACHUSETTS.

DRAG-LINE EXCAVATOR.

Application filed October 31, 1921. Serial No. 511,891.

To all whom it may concern:

Be it known that I, JOSEPH F. FITZPATRICK, a citizen of the United States, residing at Worcester, in the county of Worcester and State of Massachusetts, have invented a new and useful Drag-Line Excavator, of which the following is a specification.

This invention relates to an excavator of the type in which a bucket or the like having a scraping edge is drawn, preferably by power, in such a way as to project the scraping edge below the surface of the ground and fill the bucket. The bucket is then drawn along further to the point at which it is to be dumped. This invention relates to the bucket independent of the mechanism for dragging it along or emptying it.

The principal objects of this invention are to provide a scraping blade on the bucket in such relation to it that it will automatically be turned down into a position to dig into the earth as the bucket is dragged along; and to provide an arrangement whereby the blade will be turned up into a position level with the surface of the ground automatically when the bucket is filled so that there will be not further scraping action and the resistance to the dragging of the bucket along the ground, due to that cause, will be removed. The invention also involves improved means by which the scraping blade is turned from one position to the other and other details of construction and combinations of parts as will appear hereinafter.

Reference is to be had to the accompanying drawings, in which

Fig. 1 is a longitudinal sectional view of a drag line bucket constructed in accordance with this invention, showing it in position for digging into the ground and filling;

Fig. 2 is a front elevation of the bucket, showing it in the position it assumes when filled;

Fig. 3 is a sectional view on the line 3-3 of Fig. 4, showing the bucket in the position when filled and being dragged along; and

Fig. 4 is a plan of the bucket shown in the same position.

I have shown the invention as comprising a bucket provided with parallel side walls 10, connected by a cross bar 11, in front and a separate cross bar 12 in the rear. The latter cross bar consists of bar stock bent at its ends at right angles to engage the rear ends of the side walls 10 and secured thereto by fastening devices 13. The cross bar 11 is

provided with reduced screw threaded ends having nuts 14 thereon to fasten them to the sides 10. Thus, the cross bar 11 securely holds the sides in position at the front.

On the front ends of the side pieces 10 are shackles or hooks 15 connected with cables 16 used for drawing the device along. It will be understood that any other arrangement of cables can be used in connection with this device for drawing it back and forth.

At the bottom and rear of the two side pieces 10 are studs 20 in alignment with each other. On these are rotatably supported two hubs or brackets 22. These brackets are fixed to a scraper 23, and this scraper therefore is mounted on the studs 20 and adapted to swing thereon. This scraper constitutes the rear and part of the bottom of the bucket. The scraper 23 is provided with a plurality of teeth 24 projecting therefrom forward from the bottom and in alignment with each other across the bottom of the scraper 23. This scraper is shown of a concave form and made of sheet metal or the like. When it is in the position shown in Fig. 3 it rests back against the cross bar 12. At its upper end it is provided with an upwardly extending bracket 26 which is connected by a spring 27 with a connector 28. This connector 28 has a hook 29 at the end which extends more than half way around the cylindrical cross bar 11 and is pivoted thereon.

The spring is so made and adjusted that when it is allowed to contract it pulls the scraper 23 forward at its top into the position shown in Fig. 1. Now if the bucket is drawn along the ground and held down against its surface the teeth 24 will dig into the ground as shown in Fig. 1. As the bucket proceeds forward this action will pile the earth up on the scraper until the weight of the earth automatically swings the scraper back into the position shown in Fig. 3. The effect of this is to raise the teeth 24 out of the ground and bring them up into position level with the top of it as shown in Fig. 3. Now, the bucket can be drawn along the surface of the ground without offering any resistance other than that due to the friction of its flat bottom against the ground. In this way the filling action is very efficient and this efficiency is secured without any undue resistance to the dragging of the bucket along the ground. Furthermore, no

attention has to be paid to the operation of filling as the device works entirely automatically. Furthermore, if the action of filling is not fully accomplished during the first 5 part of the travel, the teeth are left projecting below the surface of the earth and will be able to collect additional earth in the bucket at a later period. Thus, if the area 10 worked over is sufficient, the device is certain to be filled at each operation. The bucket is emptied in any usual way. When returned back to the place where it is desired to dig, the bucket automatically moves into the position shown in Fig. 1 ready to 15 dig in at the commencement of its forward motion. In this way efficiency is increased and expensive operation reduced.

Although I have illustrated and described only a single form of the invention I am 20 aware of the fact that modifications can be made therein by any person skilled in the art without departing from the scope of the invention as expressed in the claims. Therefore, I do not wish to be limited to all the 25 details of construction herein shown and described, but

What I do claim is:

1. As an article of manufacture, a drag line excavator comprising a bucket having 30 a rear wall tiltingly mounted thereon and provided with teeth on the bottom adapted to be projected below the surface of the ground when said rear wall is tilted up at the rear.
- 35 2. A drag line excavator comprising a bucket adapted to be dragged along the ground, having a rear wall tiltingly mounted thereon and provided with a row of teeth on the bottom adapted to be projected below the surface of the ground, and yielding means for holding said teeth in that position.
- 40 3. A drag line excavator comprising a bucket adapted to be dragged along the ground, having a concave rear wall mounted thereon, the rear wall being mounted on pivots located at the bottom and near the rear of the bucket and extending from said pivots upwardly, whereby when filled with earth the weight of the earth will tip the rear wall over on its pivots rearwardly.
- 45 4. A drag line excavator comprising a bucket adapted to be dragged along the ground, having a rear wall mounted thereon

and provided with teeth on the bottom adapted to be projected below the surface 55 of the ground when said wall is empty, the rear wall being mounted on pivots located near the bottom and rear of the bucket and extending from said pivots upwardly and adapted, when filled with earth, to tip over 60 on its pivots rearwardly and raise the scraping teeth to the surface of the ground on a level with the bottom of the bucket.

5. In a drag line excavator, the combination with a pair of side walls rigidly connected together, of a scraper constituting the rear wall of the bucket pivoted to the side walls at the bottom thereof and having scraping teeth projecting forwardly thereon beyond said pivots, and yielding means for 70 holding the upper rear end of the scraper forward so as to project the teeth below the surface of the ground.

6. In a drag line excavator, the combination with a pair of side walls rigidly connected together, of a scraper constituting the rear wall of the bucket pivoted to the side walls at the bottom thereof and having scraping teeth projecting forwardly thereon beyond said pivots, and yielding means for 80 holding the upper rear end of the scraper forward so as to project the teeth below the surface of the ground, said scraping teeth being located substantially entirely at the front of the pivots, whereby, when full, the 85 weight of the earth will tip it over rearwardly into a position to draw the teeth up above the surface of the ground.

7. In a drag line excavator, the combination with a pair of side walls rigidly connected together, of a scraper constituting the rear wall of the bucket pivoted to the side walls at the bottom thereof and having scraping teeth projecting forwardly thereon beyond said pivots, yielding means for holding the upper rear end of the scraper forward so as to project the teeth below the surface of the ground, a cross bar connecting the side walls at the rear in position to limit the rearward motion of the scraper, 95 and a cross bar connecting the sides at the front to which said yielding means is connected.

In testimony whereof I have hereunto affixed my signature.

JOSEPH F. FITZPATRICK.
